C. S. KEIRSTEAD

SUSPENSORY BANDAGE

Filed April 18, 1922

Inventor:

Charles S. Keirstead.
by his atty. Mark S. Gooding.

UNITED STATES PATENT OFFICE.

CHARLES S. KEIRSTEAD, OF ANDOVER, MASSACHUSETTS.

SUSPENSORY BANDAGE.

Application filed April 18, 1922. Serial No. 555,295.

To all whom it may concern:

Be it known that I, CHARLES S. KEIRSTEAD, a citizen of the United States, residing at Andover, in the county of Essex and State of Massachusetts, have invented new and useful Improvements in Suspensory Bandages, of which the following is a specification.

This invention relates to a suspensory bandage and has for its object to provide a device of the character mentioned which is capable of being easily adjusted and fitted to the body, will be light and comfortable to wear, can be easily laundered and is also durable.

The invention consists in the combination and arrangement of parts set forth in the following specification and particularly pointed out in the claims thereof.

Referring to the drawings:

Figure 1 represents a perspective view of a suspensory bandage embodying my invention, the device being illustrated in the position it occupies when adjusted and fitted to the body of the wearer.

Fig. 2 is a view illustrating the device before being fitted to the wearer, the free end of the pouch being detached from the waistband.

Fig. 3 is a transverse section taken on the line 3—3 of Fig. 2 and illustrating the padding at the rear edge of the pouch.

Fig. 4 is a perspective view of one of the loops illustrating the hook attached at the rear thereof.

Like numerals refer to like parts throughout the several views of the drawings.

In the drawings, 5 represents a waistband embodying therein a front member 6 constructed of any suitable strong fabric at the rear of which a belt portion 7 constructed of a suitable non-elastic webbing is permanently attached. The belt portion 7 protrudes beyond each end of the front member 6, one end portion 8 thereof having a buckle 9 of well known construction fast thereto, while the other portion 10 is adapted to extend around the waist of the wearer, the end of said belt being secured to said buckle 9 in the usual well known manner.

Permanently fastened to the front member 6, preferably by being stitched thereto, is a pouch 10 preferably formed of knitted, or other suitable soft fabric. One end portion 11 of the pouch 10 which is permanently secured to the waistband 5 is gathered

at 12 and stitched to a reinforcing tape 13. A free end portion 14 of the pouch 10 is fastened by stitching to an auxiliary waistband 15 and said end portion is gathered at 16 and stitched to a reinforcing tape 17. The auxiliary waistband 15 is detachably secured to the waistband 5 as illustrated in Fig. 1 by a plurality of fastening members 18 secured to said auxiliary waistband, 65 said fastening members co-operating with other fastening members 19 fast to said waistband 5. The effect produced by gathering the material of the pouch 10 at 12 and 16 is to form an enlarged intermediate 70 portion 20 as illustrated in Fig. 2, and when the auxiliary waistband 15 is attached to the waistband 5 as illustrated in Fig. 1 the pouch 10 constitutes a receptacle in which the scrotum is supported in the usual well 75 known manner.

The front and rear edges of the pouch 10 are protected by binding tape at 21 and 22 respectively, and the central portion of the rear edge of said pouch is provided with 80 a suitable padding 23 to prevent the body of the wearer from becoming chafed from contact therewith. When the free end of the pouch 10 is attached to the waistband 5 an opening 24 is provided at the front of said 85 pouch as illustrated in Fig. 1.

In order to give the rear portion of the pouch 10 a comfortable, yielding support tapes 25 and 26 are provided, attached to the rear edge of said pouch as illustrated in 90 Fig. 2. The tape 25 connects with a loop 27, preferably constructed of elastic material, and detachably secured to the front portion of the waistband 5 adjacent to one side of 95 the pouch 10, a hook 28 fast to said loop co-operating with one of a plurality of eyes 29 fast to said waistband to fasten said loop to said waistband. The tape 26 connects with a loop 27 detachably secured to the front portion of the auxiliary waistband 15, 100 adjacent to the other side of said pouch 10, the hook 28 fast to said loop co-operating with one of a plurality of eyes 29 fast to said auxiliary waistband 15 to fasten said loop to said auxiliary waistband. After 105 the tapes 25 and 26 have been attached to their respective loops 27 and the height of the rear portion of the pouch 10 has been adjusted to fit the wearer, the end portions of said tapes are tied together at 30 and 31 respectively as illustrated in Fig. 1.

It is evident that the device as illustrated

and described is easily applied to the body because of the construction which allows one end portion of the pouch 10 to be detached from the waistband 5 while the tapes 5 25 and 26 allow the rear of said pouch to be adjusted to the height desired. The elastic loops 27 provide a yielding support for the rear of the pouch 10 and said loops may be quickly transferred from one eye 29 to 10 another of said eyes in adjusting the device to comfortably fit the body and said loops may be removed entirely from the device when the latter is laundered.

I claim:

15 1. A suspensory bandage having, in combination, a waistband, a pouch adapted to enclose the scrotum, one end of said pouch being permanently secured to said waistband, an auxiliary band fast to the other 20 end of said pouch, said auxiliary band being detachably secured to said waistband and means to yieldingly support the rear of said pouch.

25 2. A suspensory bandage having, in combination, a waistband, a pouch adapted to enclose the scrotum, one end of said pouch being permanently secured to said waistband, an auxiliary band fast to the other 30 end of said pouch, said auxiliary band being detachably secured to said waistband, a loop fast to said waistband adjacent to one side of said pouch, a second loop fast to said auxiliary band adjacent to the other side of 35 said pouch and means connecting the rear of said pouch with said loops to support said pouch at the rear thereof.

40 3. A suspensory bandage having, in combination, a waistband, a pouch adapted to enclose the scrotum, one end of said pouch being permanently secured to said waistband, an auxiliary band fast to the other 45 end of said pouch, said auxiliary band being detachably secured to said waistband, a loop fast to said waistband adjacent to one side of said pouch, a second loop fast to said auxiliary band adjacent to the other side of 50 said pouch and tapes attached to said pouch at the rear thereof and connecting with said loops whereby the height of said pouch may be varied at the rear thereof.

55 4. A suspensory bandage having, in combination, a waistband, a pouch adapted to enclose the scrotum, one end of said pouch being permanently secured to said waistband, an auxiliary band fast to the other 60 end of said pouch, said auxiliary band being detachably secured to said waistband, an elastic loop secured to said waistband adjacent to one side of said pouch, a second 65 elastic loop secured to said auxiliary band adjacent to the other side of said pouch and means connecting the rear of said pouch with said loops to support said pouch at the rear thereof.

65 5. A suspensory bandage having, in com-

bination, a waistband, a pouch adapted to enclose the scrotum, one end of said pouch being permanently secured to said waistband, an auxiliary band fast to the other 70 end of said pouch, said auxiliary band being detachably secured to said waistband, an elastic loop detachably secured to said waistband adjacent to one side of said pouch, a 75 second elastic loop detachably secured to said auxiliary band adjacent to the other side of said pouch and tapes attached to said pouch at the rear thereof and connecting with said loops whereby the height of said pouch may be varied at the rear thereof.

80 6. A suspensory bandage having, in combination, a waistband, a pouch adapted to enclose the scrotum, one end of said pouch being permanently secured to said waistband, an auxiliary band fast to the other 85 end of said pouch, a plurality of fastening members fast to said waistband, a plurality of other fastening members fast to said auxiliary band and co-operating with said first-named fastening members to detachably secure said auxiliary band to said waistband, 90 a loop fast to said waistband adjacent to one side of said pouch, a second loop fast to said auxiliary band adjacent to the other side of said pouch and tapes connecting the rear of said pouch with said loops to support 95 said pouch at the rear thereof.

7. A suspensory bandage having, in combination, a waistband, a pouch adapted to enclose the scrotum, one end of said pouch being permanently secured to said waistband, an auxiliary band fast to the other 100 end of said pouch, said auxiliary band being detachably secured to said waistband, a plurality of fastening members secured to said waistband adjacent to one side of said 105 pouch, a plurality of other fastening members secured to said auxiliary band adjacent to the other side of said pouch, a loop detachably secured to said fastening members at each side of said pouch and tapes attached to said pouch at the rear thereof 110 and connecting with said loops whereby the height of said pouch may be varied at the rear thereof.

8. A suspensory bandage having, in combination, a waistband, a pouch adapted to enclose the scrotum, one end of said pouch being permanently secured to said waistband and the other end thereof being detachably secured thereto, said pouch being provided 120 with a padded edge at the rear thereof and means to support the rear of said pouch at the front of said waistband.

In testimony whereof I have hereunto set my hand in presence of two subscribing 125 witnesses.

CHAS. S. KEIRSTEAD.
